DISCONNECTING SWITCH FOR HIGH CURRENT

Harold H. Rugg and Herbert J. Crabbs, Pittsburgh, Pa., assignors to Westinghouse Electric Corporation, East Pittsburgh, Pa., a corporation of Pennsylvania

Application June 30, 1954, Serial No. 440,474

9 Claims. (Cl. 200—162)

Our invention relates, generally, to electric switches and, more particularly, to disconnecting switches for power distribution systems.

An object of our invention is to provide a disconnecting switch which shall have a high current capacity and which shall be relatively simple in construction.

Another object of our invention is to provide a multiple-blade disconnecting switch in which the blades are disposed to form a hollow square.

A further object of our invention is to provide a multiple-blade disconnecting switch which shall be relatively easy to operate.

Still another object of our invention is to provide a disconnecting switch having two sets of blades which engage fixed contact members at different times during the closing operation.

A still further object of our invention is to provide a multiple-blade disconnecting switch having blades disposed in different levels but operating about the same hinge axis.

Other objects of our invention will be explained fully hereinafter or will be apparent to those skilled in the art.

In accordance with one embodiment of our invention, four double-blade switch members are disposed to form substantially a hollow square. Each blade is generally of an L shape and the blades are so assembled in reversed relation that they hinge about the same axis which lies substantially in line with the adjacent edges of the longer legs of the L-shaped blades. The blades are so mounted that the blades in the lower level engage the break tongue before the blades in the upper level during closing of the switch, thereby reducing the force required to close the switch.

For a better understanding of the nature and objects of the invention, reference may be had to the following detailed description, taken in conjunction with the accompanying drawings, in which:

Figure 1 is a view, in front elevation, of a disconnecting switch embodying the principal features of the invention;

Fig. 2 is a reduced view, in side elevation, of the switch illustrated in Fig. 1;

Fig. 3 is a view, in side elevation, of one of the switch blades utilized in the disconnecting switch;

Fig. 4 is a view, in front elevation, of the hinge tongue of the switch;

Figs. 5 and 6 are enlarged views, in end and side elevation, respectively, of the contact portion of the break tongue of the switch, and

Figs. 7 and 8 are reduced views, in side and front elevation, respectively, of the break tongue.

Referring to the drawings, and particularly to Figs. 1 and 2, the disconnecting switch shown therein comprises a channel-shaped base 10, two insulators 11 and 12, which are attached to the base 10, a break tongue terminal member 13 attached to the insulator 11, a hinge tongue terminal member 14 attached to the insulator 12, two pairs

2

of switch blades 15 which are disposed in a lower level and two pairs of switch blades 16 which are disposed in an upper level, as viewed in Fig. 2. It is to be understood that the lower level is nearer the base 10 than the upper level.

The base 10 is preferably composed of sheet metal and it may be attached to suitable supports (not shown) by bolts inserted into openings 17 provided in the base. The insulators 11 and 12 may be of the usual construction and attached to the base 10 by bolts 18 inserted in openings 19 provided in the base of each insulator.

As shown most clearly in Fig. 4, the hinge tongue terminal member 14 comprises a base portion 21 having openings 22 and 23 therein for receiving bolts 24 for attaching the terminal member to the insulator 12. The terminal member 14 is provided with four sides having openings 25 therein for attaching electrical conductors (not shown) to the terminal member. Thus, if desired, bus bars or conductors disposed in the form of a hollow square may be attached to the terminal member 14.

The member 14 is also provided with two hinge tongues 26 to which the switch blades 15 and 16 are attached, as will be more fully described hereinafter. Each hinge tongue has an opening 27 therethrough for receiving a bolt for attaching the switch blades. The terminal member 14 is preferably composed of copper or other suitable electrical conducting material.

As shown most clearly in Figs. 5, 6 and 7, the break tongue terminal member 13 comprises a base portion 28 having openings 22 and 23 therein for receiving bolts 24 for attaching the terminal member to the insulator 11. The terminal member 13 also has four sides provided with openings 25 for attaching electrical conductors to the terminal member. Electrical conductors arranged in the form of a hollow square may be attached to the terminal member 13.

The member 13 is provided with two break tongues 29 which may be brazed or welded to the terminal member. As shown in Fig. 5, each tongue 29 comprises a relatively narrow upper portion 31 and a wider lower portion 32. As will be explained more fully hereinafter, the upper portion 31 is engaged by a pair of switch blades 16 which are spaced relatively closely together. The lower portion 32 is engaged by a pair of switch blades 15 which are spaced farther apart than the blades 16. Each break tongue 29 has two grooves 33 therein for receiving bolts which tie the switch blades together.

One of the switch blades 16 is shown in Fig. 3. As shown, the blade 16 is generally of an L shape having a long leg 34 and a short leg or offset hinge portion 35. The blade is provided with a hole 36 in the offset portion for receiving the bolt for pivotally attaching the blade to the hinge tongue. It is also provided with holes 37 and 38 for receiving pins or bolts for tying the switch blades together. Embossed contact surfaces 39 in the form of ridges extending outwardly from the surface of the blade portion 34 are provided for engaging the break tongue of the switch. The contact surfaces 39 are preferably silver plated to decrease the contact resistance. Silver plated contact areas 40 are also provided around the hole 36. The blades 15 are similar to the blades 16 with the exception that they are shorter in length. The blades 15 and 16 are preferably composed of the same material, such as copper, as the terminal members 13 and 14.

As shown in Figs. 1 and 2, a pair of switch blades 15 and a pair of switch blades 16 are attached to each of the two hinge tongues 26 by bolts 41 having nuts 42 threaded thereon in spaced relation. Spring washers 43 are provided for maintaining contact pressure between the switch blades and the hinge tongues.

As also shown in Fig. 2, the short legs or offset portions 35 of the L-shaped blades 15 are reversed with respect to the short legs 35 of the L-shaped blades 16, thereby making it possible to mount the blades 15 and 16 in two levels and at the same time hinge all eight blades on two hinge tongues about the same axis which is located substantially in line with adjacent edges of the switch blades. As previously explained, the switch blades 16 are spaced relatively closely together and they engage opposite sides of the hinge tongue 26 directly.

The blades 15 are spaced farther apart with one of the blades 15 engaging the outer side of each blade 16. However, since all four blades on one hinge tongue are connected to the tongue by one bolt 41 and one pair of spring washers 43, the contact pressure is equalized between the blades and the hinge tongue, thereby assuring an equal distribution of current in the four blades on one hinge tongue.

As shown in Fig. 2, the upper ends of each pair of switch blades 16 are tied together by a bolt 41 having nuts 42 and spring washers 43 disposed thereon. A spacing member 44 is disposed on the bolt 41 between each pair of blades 16 to maintain the upper ends of the blades in spaced relation. As previously explained, the bolt 41 enters a groove 33 in the break tongue 29 when the switch blades are closed.

The upper ends of each pair of blades 15 are tied together by a bolt 41 in the same manner as the blades 16 are tied together. A spacing member 45 is provided between each pair of blades 15 to maintain these blades in the proper spaced relation.

The two pairs of blades 16 are tied together intermediately of the ends of the blades by pins 46 which extend through the two pairs of switch blades 16 and through two brackets 47 which are disposed side-by-side between the two pairs of blades 15. A spacing member 44 is provided on the pin 46 between each pair of blades 16 and a spacing member 48 is provided on the pin 46 between each inner blade 16 and one of the brackets 47.

Both pairs of blades 15 are tied together and attached to the brackets 47 by pins 49 which extend through the blades 15 and the brackets 47. Spacing members (not shown) are provided on the pins 49 between each pair of blades 15 to maintain the blades in the proper spaced relation. Cotter keys 51 may be inserted through the pins 46 and 49 to retain the pins in the switch blades.

In this manner, all of the blades 15 and 16 of the switch are so tied together that they are operated at the same time. Openings 52 are provided in the brackets 47 for receiving a bolt or pin (not shown) which may be connected to an operating mechanism suitable for operating the switch blades. Thus, all of the switch blades are operated simultaneously.

However, the switch blades are so mounted and the break tongues 29 are so constructed by making the portions 32 wider than the portions 31 that the switch blades 15 engage the portions 32 of the break tongues 29 slightly before the blades 16 engage the portions 31 of the tongues 29 during the closing operation. Hence, contact pressure is applied to the blades 15 slightly before contact pressure is applied to the blades 16. Thus, the force required to close the switch blades is reduced.

As explained hereinbefore, the bus bars or conductors are connected to the terminal members 13 and 14 in a hollow square formation. The four pairs of switch blades are disposed in substantially a hollow square formation. Therefore, the switch blades are in the proper relation to carry heavy currents with a minimum cross-sectional area of the switch blades. As also explained hereinbefore, equal distribution of current between the switch blades is obtained by connecting the blades to each hinge tongue by a single bolt and one set of spring washers, thereby maintaining the same contact pressure on the blades connected to the same hinge tongue.

The two bolts 41 which connect the blades to the hinge

tongues have the same axis which extends transversely of the hinge tongues. It will be noted that the inner ends of these bolts are extended to within a short distance of each other. Likewise, the inner ends of the bolts 41 which tie the upper ends of the switch blades together are extended to within a short distance of each other. Thus, the inner ends of these bolts will be engaged to prevent excessive bending of the hinge and break tongues in the event of a heavy short-circuit current, the force of which has a tendency to draw the switch blades together. The brackets 47 also prevent the switch blades from being drawn together under short circuit conditions.

From the foregoing description, it is apparent that we have provided a disconnecting switch which is relatively simple and compact in construction and which has the capacity to carry relatively large amounts of current without damage to the switch members. The blades of the switch are arranged in a manner to obtain an even distribution of current flow through the switch blades. Also, certain of the blades are of duplicate construction, thereby facilitating their manufacture.

Since numerous changes may be made in the above-described construction and different embodiments of the invention may be made without departing from the spirit and scope thereof, it is intended that all matter contained in the foregoing description or shown in the accompanying drawings shall be interpreted as illustrative and not in a limiting sense.

We claim as our invention:

1. In an electric switch, in combination, a support hinge tongue terminal means mounted on said support, break tongue terminal means also mounted on the support and having contact surfaces thereon in an upper level and a lower level, the surfaces on the lower level being in planes offset laterally from the planes of the surfaces on the upper level, a plurality of pairs of switch blades mounted on the hinge tongue terminal means and movable to engage the break tongue terminal means, said pairs of switch blades being disposed in an upper level and a lower level to form substantially a hollow square and having overlapping hinge portions, said blades being disposed in offset planes corresponding to the planes of the contact surfaces on the break tongue terminal means, and all of said blades hinging about a common axis extending transversely of the switch through the overlapping portions of all of said blades and the hinge tongue terminal means.

2. In an electric switch, in combination, two spaced insulating supports, hinge tongue terminal means mounted on one of said supports, break tongue terminal means mounted on the other support and having contact surfaces thereon in an upper level and a lower level, the surfaces on the lower level being in planes offset laterally from the planes of the surfaces on the upper level, a plurality of pairs of switch blades mounted on the hinge tongue terminal means and movable to engage the break tongue terminal means, said pairs of switch blades being disposed in an upper level and a lower level to form substantially a hollow square and having overlapping hinge portions, said blades being disposed in offset planes corresponding to the planes of the contact surfaces on the break tongue terminal means, and all of said blades hinging about a common axis extending transversely of the switch through the overlapping portions of all of said blades and the hinge tongue terminal means, said axis lying substantially in line with the adjacent edges of the switch blades.

3. In an electric switch, in combination, a support hinge tongue terminal means mounted on said support, break tongue terminal means also mounted on the support and having contact surfaces thereon in different levels and in planes offset laterally, a plurality of pairs of switch blades mounted on the hinge tongue terminal means and movable to engage the break tongue terminal

means, said pairs of switch blades being disposed in an upper level and a lower level to form substantially a hollow square and having overlapping hinge portions, and all of said blades hinging about a common axis extending transversely of the switch through the overlapping portions of all of said blades and the hinge tongue terminal means, the switch blades in one level engaging the contact surfaces on the break tongue in one level before the blades in the other level engage the contact surfaces in the other level on the break tongue during closing of the switch.

4. In an electric switch, in combination, two spaced insulating supports, hinge tongue terminal means mounted on one of said supports, break tongue terminal means mounted on the other support and having contact surfaces thereon in a lower level and an upper level and in planes offset laterally, a plurality of pairs of switch blades mounted on the hinge tongue terminal means and movable to engage the break tongue terminal means, said pairs of switch blades being disposed in an upper level and a lower level to form substantially a hollow square and having overlapping hinge portions, and all of said blades hinging about a common axis extending transversely of the switch through the hinge tongue terminal means and the overlapping hinge portions of the blades, the switch blades in the lower level engaging the contact surfaces on the break tongue in the lower level before the blades in the upper level engage the contact surfaces in the upper level during closing of the switch.

5. In an electric switch, in combination, two spaced insulating supports, hinge tongue terminal means mounted on one of said supports, break tongue terminal means mounted on the other support and having contact surfaces thereon in an upper level and a lower level, the surfaces on the lower level being in planes offset laterally from the planes of the surfaces on the upper level, a plurality of pairs of switch blades having offset hinge portions mounted on the hinge tongue terminal means and movable to engage the break tongue terminal means, said pairs of switch blades being disposed in an upper level and a lower level with the offset hinge portions of the blades overlapping each other, the thickness of the overlapping portion of each blade being no less than the thickness of the rest of the blade, said blades being disposed in offset planes corresponding to the planes of the contact surfaces on the break tongue terminal means, one pair of blades in the upper level and one pair of blades in the lower level being hinged on one pin which extends through the overlapping portions of the two pairs of blades, another pair of blades in the upper level and another pair of blades in the lower level being hinged on another pin which extends through the overlapping portions of the two other pairs of blades, and both of said pins being on the same axis which extends transversely of the hinge tongue terminal means.

6. In an electric switch, in combination, two spaced insulating supports, hinge tongue terminal means mounted on one of said supports, break tongue terminal means mounted on the other support and having contact surfaces thereon in an upper level and a lower level, the surfaces on the lower level being in planes offset laterally from the planes of the surfaces on the upper level, a plurality of pairs of switch blades having offset hinge portions mounted on the hinge tongue terminal means and movable to engage the break tongue

terminal means, said pairs of switch blades being disposed in an upper level and a lower level with the offset hinge portions of the blades overlapping each other, the thickness of the overlapping portion of each blade being no less than the thickness of the rest of the blade, said blades being disposed in offset planes corresponding to the planes of the contact surfaces on the break tongue terminal means, one half of said blades being hinged on one pin which extends through two pairs of blades and the other half of the blades being hinged on another pin which extends through two other pairs of blades, both of said pins being on a line which extends transversely of the hinge tongue terminal means.

7. In an electric switch, in combination, two spaced insulating supports, a hinge terminal mounted on one of said supports, said hinge terminal having two spaced hinge tongues thereon, a break terminal mounted on the other support, said break terminal having two spaced break tongues thereon, each break tongue having two contact surfaces on each side in offset planes, two pairs of generally L-shaped switch blades mounted on each hinge tongue and movable to engage the break tongues, said blades being disposed in offset planes corresponding to the planes of the contact surfaces on the break tongues, the short legs of one pair of L-shaped blades on each hinge tongue being reversed with respect to the short legs of the other pair of blades on said tongue, all of the blades on each hinge tongue being hinged on one pin which extends through the short legs of the blades, and the pins in both tongues being on the same axis which extends transversely of the hinge terminal.

8. In an electric switch, in combination, two spaced insulating supports, a hinge terminal mounted on one of said supports and having a hinge tongue thereon, a break terminal mounted on the other support and having a break tongue thereon, the break tongue having two contact surfaces on each side in offset planes, two pairs of switch blades pivotally mounted on the hinge tongue in offset planes corresponding to the planes of the contact surfaces on the break tongue, all of said blades hinging on one pin which extends through the hinge tongue and the blades, and all of said blades being movable together to engage the break tongue.

9. In an electric switch, in combination, two spaced insulating supports, a hinge terminal mounted on one of said supports, said hinge terminal having two spaced hinge tongues thereon, a break terminal mounted on the other support, said break terminal having two spaced break tongues thereon, each break tongue having two contact surfaces on each side in an upper level and a lower level, the contact surfaces on the lower level being spaced farther apart than those in the upper level, two pairs of switch blades pivotally mounted on each hinge tongue in an upper level and a lower level, the blades in each level being spaced in accordance with the spacing of the contact surfaces in the corresponding level, all of said blades on one hinge tongue being hinged on one pin which extends through the tongue and the blades, and all of said blades being movable together to engage the break tongues.
